UNITED STATES PATENT OFFICE.

CHARLES GABEL, OF HAWKEYE, IOWA.

VETERINARY OBSTETRICAL INSTRUMENT.

No. 886,363.

Specification of Letters Patent.

Patented May 5, 1908.

Application filed January 3, 1908. Serial No. 409,222.

To all whom it may concern:

Be it known that I, CHARLES GABEL, a citizen of the United States, residing at Hawkeye, in the county of Fayette and State of Iowa, 5 have invented certain new and useful Improvements in Veterinary Obstetrical Instruments, of which the following is a specification.

This invention relates to veterinary instruments, and more particularly to obstetrical instruments.

The object of this invention is to provide an instrument of the character above described which will enable the operation to be 15 quickly and safely performed.

Another object of the invention is to provide a veterinary obstetrical instrument which is exceedingly light in construction, yet durable, convenient in use and positive 20 in action.

With these ends in view, I make use of certain component and coöperative parts which I deem sufficiently improved and operative to carry out the fundamental principles 25 of my invention, however, I wish it to be understood that I do not limit myself to the exact details of construction as shown and described, as various minor changes may be resorted to without sacrificing any of 30 the advantages of this invention.

For a clear understanding of the merits and advantages of the invention, reference is to be had to the accompanying drawings forming a part of this specification, where- 35 in:—

Figure 1, is a perspective view, Fig. 2, is an enlarged detail view, Fig. 3, is a modified form, and Fig. 4, is a detail view of the modification.

40 Referring by numerals to the drawings, 1 represents a handle composed of two wires bent to form a loop and twisted to form an elongated shank 2, at the other end of which the respective branches or arms 3, 4, 5, and 6, 45 are coiled so as to form spiral springs 7, 8, 9, and 10, with their free ends projecting upwardly and terminating in small loops or eyes 11, 12, 13, and 14. The branch or arm 3, however, is so shaped as to form an additional arm 15, which is provided with two loops or eyes 16, and a protruding lip 17, which aids in the insertion of the instrument. Passing through the eyes 11, 12, 13, and 14, is a cord 18, the respective ends of 55 which pass through the respective eyes 16,

and extend downward parallel with the arm 15, and over two of the arms and are secured to a handle 19, by means of which the arms may be contracted.

In Figs. 3 and 4, I have shown a modification wherein the arms are provided with auxiliary spiral springs 20, having their respective ends 21 and 22, secured to the arms in such a manner that the said arms will be normally held in a flaring or extended position, they may however, be contracted by means of the cord 18, as in the form shown in Figs. 1 and 2.

Normally the arms are sprung apart, and to collapse the same it is necessary to pull 60 down on the handle 19, to which the cord is attached, thus causing the respective arms to close up within the lip 17, and to remain rigidly in this position so that the instrument 65 can be readily and safely inserted into the 70 vagina. When the fetus is reached the cord is released whereupon the arms spring apart so as to receive the fetus, and the instrument is gently pushed in until the fetus is embraced after which the cord is pulled so as to 75 contract the arms sufficiently to insure a firm grip, and then the instrument is pulled out by the handle and cord, as the animal labors.

Having thus described my invention, what I claim as new and desire to secure by Letters Patent, is:—

1. In an obstetrical instrument, a series of wires twisted to form a handle, each wire being wound to form a spiral spring and terminating in a diverging end, and means for contracting the ends, substantially as specified.

2. In an obstetrical instrument, a series of wires bent and twisted to form a looped handle and a shank, the respective ends of the wires being coiled to form spiral springs, said ends 95 projecting from said springs, and means for contracting said ends, substantially as specified.

3. In an obstetrical instrument, a series of wires bent and twisted to form a handle and its shank, the respective ends of the wires being coiled to form springs and projecting upward from said springs, the free ends of the wires being provided with loops, and a cord passing through said loops, substantially 100 as specified.

4. In an obstetrical instrument, a series of wires bent and twisted to form a handle and its shank, the respective ends of the wires being coiled to form springs and projecting 105 as specified.

upward from said springs, the free ends of the wires being provided with loops, one of the wires being bent so as to form a lip, two loops adjacent to the lip, a cord being passed through the loops with its respective ends passed downward parallel to the arm supporting the lip, said cord being secured by

its respective ends to a handle, substantially as specified.

CHARLES GABEL.
